FOREIGN PATENT DOCUMENTS

GB 6372471 * 6/2024

Primary Examiner — Paula Allen Greene(74) *Attorney, Agent, or Firm* — Jon Gibbons; Fleit
Intellectual Prope(57) **CLAIM**

The ornamental design for modular vase as shown and described.

DESCRIPTION

FIG. 1 is a perspective view of the modular vase;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a perspective explosion view with a first bottom
piece thereof; and,
FIG. 9 is a perspective explosion view with a second bottom
piece thereof.
Broken lines shown in the figures form no part of the
claimed design.
